(57) **CLAIM**

The ornamental design for a swaddle, as shown and described.

DESCRIPTION

FIG. 1 is a perspective view of a swaddle, showing our new design in a first configuration;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a perspective view of a swaddle, showing our new design in a second configuration;

FIG. 9 is a front view thereof;

FIG. 10 is a rear view thereof;

FIG. 11 is a side view thereof;

FIG. 12 is another side view thereof;

FIG. 13 is a top view thereof; and,

FIG. 14 is a bottom view thereof.

The broken line disclosure forms no part of the claimed design.

1 Claim, 9 Drawing Sheets
